DESIGN FOR A WELDING ELECTRODE HOLDER

Carl L. Wood, Richmond, Calif.

Application October 2, 1943, Serial No. 111,251

Term of patent 14 years

To all whom it may concern:

Be it known that I, Carl L. Wood, a citizen of the United States, residing at the city of Richmond, county of Contra Costa, and State of California, have invented a new, original, and ornamental Design for Welding Electrode Holder, of which the following is a specification, reference being had to the accompanying drawing, forming part thereof.

Fig. 1 is a perspective view of a welding electrode holder showing my new design;

Fig. 2 is a side elevational view thereof;
Fig. 3 is a side elevational view of the side opposite that shown in Fig. 2; and

Fig. 4 is a view of the open end of the holder.
I claim:

The ornamental design for a welding electrode holder, as shown.

CARL L. WOOD.
